UNITED STATES PATENT OFFICE

HARRY F. WATERS, OF NEW YORK, N. Y.

DESIGN FOR AN OVERTSHOE

Application filed March 2, 1933. Serial No. 47,381. Term of patent 14 years.

To all whom it may concern:

Be it known that I, HARRY F. WATERS, a citizen of the United States of America, residing in New York, in the county of New York, State of New York, have invented a new, original, and ornamental Design for an Overshoe, of which the following is a companying drawing, forming a part thereof. The figure is a perspective view of an overshoe showing my new design.

I claim:

The ornamental design for an overshoe, as shown.

HARRY F. WATERS.
